DISPLAY STAND FOR HOSIERY

Filed Aug. 21, 1924

Inventor:
Norman L. Stevens,
by Wm. F. Friedrich,
Attest.

UNITED STATES PATENT OFFICE.

NORMAN L. STEVENS, OF BLOOMFIELD, NEW JERSEY, ASSIGNOR TO THE MEYERCORD COMPANY, A CORPORATION OF ILLINOIS.

DISPLAY STAND FOR HOSIERY.

Application filed August 21, 1924. Serial No. 733,311.

To all whom it may concern:

Be it known that I, NORMAN L. STEVENS, a citizen of the United States, residing in Bloomfield, county of Essex, State of New Jersey, have invented a certain new and useful Improvement in Display Stands for Hosiery, and declare the following to be a full, clear, and exact description of the same, such as will enable others skilled in the art to which it pertains to make and use the same, reference being had to the accompanying drawings, which form a part of this specification.

The present invention has for its object to produce a simple, novel and attractive device for use in stores for the purpose of displaying hosiery in connection with advertising pictures or other matter.

A further object of the present invention is to produce a device of the character described which will be small and compact so as to take up very little room in shipping the same.

The various features of novelty whereby my invention is characterized will herein-after be pointed out with particularity in the claims; but, for a full understanding of my invention and of its objects and advantages, reference may be had to the following detailed description taken in connection with the accompanying drawings, wherein:

Figure 1 is a front view and Fig. 2 is a rear view of a device arranged in accordance with my invention, opened up for use; Fig. 3 is a side view of the device; Fig. 4 is similar to Fig. 2, showing only a fragment of the device, the arms thereon being shown in a different position than in Fig. 2; and Fig. 5 is a section taken approximately on line 5—5 of Fig. 2.

Referring to the drawing, 1 represents a panel that is preferably widened at the bottom as indicated at 2. Near the bottom of the panel is a long transverse slot 3. The space bounded by the heavy black line 4 is adapted to contain illustrations and other advertising matter. On the rear side of the panel is a suitable brace 5 hinged at its upper end to the panel as indicated at 6, so that the brace may either be swung out into a supporting position as shown in Fig. 3, or be laid flat against the back of the panel. On the rear face of the panel, at the sides and near the top, are fastened two small

plates 7 and 8 bowed at the center to form 55 parallel vertical open bearings. 9 and 10 are two heavy wires or small rods, each having an end 11 bent laterally at right angles; the parts being so constructed and arranged that the bent ends fit into bearings or openings formed between the plates 7 and 8 and the back of the panel, so that the members 9 and 10 may be supported in horizontal positions either parallel with the plane of the panel or at an angle to such plane. The 60 free end of each arm may also be bent laterally, as indicated at 12, preferably in the upward direction. For shipping purposes, the arms are simply lifted out of their supporting bearings or sockets and laid flat 70 against the panel.

In using the device, the parts may be adjusted into the position shown in Figs. 1 to 3, and stockings, either all of one color or various colors, may be hung on the projecting arms at opposite sides of the panel, the feet being brought down behind the panel and drawn outwardly through the long slot. In this way the feet and the tops of the stockings may be emphasized. If it be desired, because of lack of display space, or for other reasons, the arms may be swung through angles of 180 degrees so that each extends entirely across the panel and projects beyond the latter on the side opposite 80 that on which it is supported, as shown in Fig. 4. Or, if desired, the arms may be adjusted to an intermediate position, between the two extreme positions illustrated in Figs. 2 and 4 respectively. 90

While I have illustrated and described with particularity only a single preferred form of my invention, I do not desire to be limited to the exact structural details thus illustrated and described; but intend to 95 cover all forms and arrangements which come within the definitions of my invention constituting the appended claims.

I claim:

1. A device of the character described comprising a solid panel, means for supporting the panel in a more or less upright position, said panel having a long transverse slot through the same near the bottom, and lateral arms near the upper end of the panel, 105 the parts being so proportioned and the slot being of such a height and width that one end of each of a plurality of stockings hung

upon said arms may be passed through the slot from the rear of the panel and be exhibited in front of the panel.

2. A device of the character described, comprising a solid panel having on its front face a large advertising space and having near the bottom a long transverse slot, arms projecting laterally from the panel near the upper end, and means for supporting the panel in a more or less upright position, the parts being so proportioned and the slot being of such a height and width that one end of each of a plurality of stockings hung upon said arms may be passed through the slot from the rear of the panel and be exhibited in front of the panel.

3. A device of the character described comprising a solid panel having a long transverse slot through the same, laterally projecting arms on the panel above the slot, and means for supporting the panel in a more or less upright position, the parts being so proportioned and the slot being of such a height and width that one end of each of a plurality of stockings hung upon said arms may be passed through the slot from the rear of the panel and be exhibited in front of the panel.

4. A device of the character described comprising a solid panel having a long transverse slot through the same, arms connected to the upper portion of the panel near the sides thereof so as to be adjustable into various positions, and means for supporting the panel in a more or less upright position, the parts being so proportioned and

the slot being of such a height and width that one end of each of a plurality of stockings hung upon said arms may be passed through the slot from the rear of the panel 40 and be exhibited in the front of the panel.

5. A device of the character described comprising a solid panel having a long transverse slot near its lower end, a brace hinged to the back of the panel to support it 45 in a more or less upright position or be swung flat against the panel, and arms hinged to the upper portion of the panel so as to be capable of swinging between positions in which each projects beyond the 50 edges adjacent to which it is hinged and positions in which each extends across the rear face of the panel.

6. A device of the character described comprising a solid panel having a long 55 transverse slot through the same, a supporting brace hinged to the rear face of the panel, elements arranged on the rear of the panel above said slot and near the sides of the panel having holes extending vertically 60 therethrough, and a pair of arms each having an end turned at right angles thereto and adapted to fit into one of said holes, the parts being so proportioned and the slot being of such a height and width that one 65 end of each of a plurality of stockings hung upon said arms may be passed through the slot from the rear of the panel and be exhibited in front of the panel.

In testimony whereof, I sign this specification.

NORMAN L. STEVENS.
